TAPE SELVAGE FRAME

Richard T. Osteen, Greenville, S. C., assignor to
Walker Manufacturing Company, Inc., Philadelphia, Pa., a corporation of Pennsylvania

Application June 17, 1943, Serial No. 491,216

8 Claims. (Cl. 139—92)

The object of the invention is to provide improvements in tape selvage harnesses and especially in the heddle bar mountings within the frames and the supports therefor.

Another object is to provide a one-piece tape selvage frame, comprising upper and lower parallel sections, which are preferably of increased stiffness, and parallel side sections, connecting the corresponding end portions of said first-mentioned sections, said side sections being relatively resilient transversely.

A further object is to provide a one-piece frame of this type from a pair of similar, initially separate metallic members, which are riveted, welded or otherwise secured together in unitary relation.

Still another object is to provide a frame of this character having side sections provided with aligned apertures, in combination with abbreviated heddle bars also having apertures and extending through the apertures in said frame sections, the metal of a side frame section being squeezed or otherwise deformed or so deflected from its initial condition or position, as to enter one of the apertures of each intervening heddle bar, to secure the same in fixed relationship therewith, while the opposite end portion of each bar extends loosely through the aperture in the opposite side section, and is normally prevented from release or escapement therefrom by the inherent resiliency of said side sections, augmented by the longitudinal tension placed upon them. However, in order to still further insure against the bars accidental escape, there is provided a transversely arranged pin or the like, which extends through the bar aperture and engages the outer surface of said adjacent side section.

A still further object is to provide the combination of a frame of this nature, in which the side sections are provided additional apertures adjacent to their opposite ends, and resilient bails having flattened, hooked end portions normally entering said apertures, and removable therefrom by expanding said bail by flexing its sides or legs outwardly.

With the objects thus briefly stated, the invention comprises further details of construction and operation, which are hereinafter fully brought out in the following description, when read in conjunction with the accompanying drawing in which Fig. 1 is an elevational view of a tape selvage frame comprising one embodiment of the invention; Fig. 2 is an enlarged fragmentary section on the line 2—2 of Fig. 1; Fig. 3 is an enlarged fragmentary section on the line

3—3 of Fig. 1; Fig. 4 is a fragmentary view of a portion of said frame distorted so as to release heddles from one of the heddle bars, the opposite ends of the entire construction being to all intents and purposes duplicates; Fig. 5 is an enlarged fragmentary view showing a modified form of bar-securing means engaging within a cut-away position of the heddle bar instead of extending through an actual aperture therein; and Fig. 6 is a section on the line 6—6 of Fig. 5, the resilient clip being shown in elevation.

Referring to Figs. 1 to 4 of the drawing, it will be understood that the frame per se may comprise a single piece of ribbon-like wire or similar material, but in its preferred embodiment consists of two like similar U-shaped members, which can be economically stamped and formed from two exactly similar pieces of metal. One of these members comprises a side section 1 connecting two oppositely positioned end sections 2, while the other member is of the same shape and comprises a side section 1' and end section 2'. The ends of the two pieces are assembled so that they preferably overlap, thereby providing a unitary joint formed in any suitable manner, as by spot-welding at 3, or by piercing the ends to provide pairs of aligned apertures in which rivets or so-called Bostick staples can be inserted.

Each of said side sections is provided with slender, elongated apertures 4 fairly close to the adjacent end sections, and into opposite pairs of which apertures normally extend the flattened, inwardly directed, hook terminals 5 of a bail, which additionally comprises resilient legs 6, connected together at their outer ends by centrally positioned sections 7, which are surrounded by or otherwise secured to the tapes 8, cables, or the like, which comprise the usual harness or means for alternately elevating and depressing the improved frame and the heddles carried thereby. Either or both of said bails are released from the said frame by spreading the legs 6 outwardly in opposite directions, as shown at the top of Fig. 1.

Inwardly from the respective pairs of bail-receiving apertures 4, are additional pairs of slender, aligned apertures 9 and 9' in the oppositely positioned side sections 1 and 1'. Referring to one of these pairs, of which the other pair is a duplicate, a relatively short heddle bar 10, having apertures 11 and 12 in its end portions, is inserted into the aperture 9, so that its aperture is substantially centrally positioned with respect to the adjacent portion of the surrounding side section, whereupon the metal 13 of

the side section upon the opposite sides of its aperture 9 is pinched or squeezed together into the bar aperture 11, thereby loosely but permanently securing said bar in operative position, in unitary association with said side section.

After both of said bars have been secured in this manner, they are inserted through the usual eyes in the end portions of any well-known type of heddle 14, after which the opposite free end of each bar is inserted in the aligned aperture in the opposite side frame section aperture 9', by first flexing said side section outwardly as shown in Fig. 4, which is also the position and arrangement of the respective parts when removing and/or substituting a new heddle for one that has already been in use upon said bars. After the free end of each bar has been inserted through the second side frame section until the aperture 12 in the bar is outside of said section, a fastening member 15 of any available and suitable form is inserted through the bar aperture and bent or otherwise locked in place, so as to thereby secure said second side section against becoming accidentally dislodged from the adjacent end portion of the heddle bar supported by it. By removing said fastening means, the adjacent side frame section can be easily slipped laterally away from the respective heddle bars and the heddles thereon removed and replaced at will.

While said fastening means is shown in Figs. 1 and 3 as extending through the heddle bar apertures, in Figs. 5 and 6 is shown a modified form of said means, consisting of any suitable form of expansible, resilient clip 16, having oppositely positioned, parallel legs 17, which may normally rest within grooves pressed in the opposite sides of said bars adjacent to said side frame sections, or instead may depend upon spaced, angularly converging end portions 18 and 19, respectively at the head and foot of said means, yieldingly entering oppositely directed cut-out portions 20 in the upper and lower edges of said bars. This modified form of locking means is illustrated in order to indicate clearly that the invention is not dependent in any way to the exact form of locking means that may be used, and that, instead of apertures, cut-out portions, grooves, and the like, may be employed equally well for this purpose.

In any case, it will be noted that the security of the heddle bars within their supporting side frame sections is not dependent upon the locking means, as in fact little or no pressure or force is applied thereto, since the longitudinal tension exerted upon said side sections by the straps 3 or the like, through the intervening bails, is sufficient to prevent the escape of said bars from said frame sections, with consequent loss of the bars therefrom when not intended.

Fig. 4 illustrates substantially the position of the side section 17, as it is temporarily flexed outwardly from its normal rectilinear position, as shown in dot-and-dash lines. By flexing said side section outwardly beyond the end of the heddle bar 10, after first removing the fastening member 15, as many of the heddles 14 as may be desired can be slipped from said bar, and the same heddles replaced or others substituted therefor, when and as desired. After the said section has been returned to its normal position, said fastening means is replaced to prevent accidental dislodgement of said section until again desired.

Having thus described my invention, what I

claim and desire to protect by Letters Patent of the United States is:

1. A tape selvage frame, comprising side and connecting end sections, said side sections being provided with a pair of aligned apertures, a heddle bar extending through said apertures and itself having a cut-away portion positioned in alignment with one side section, said last-mentioned side section being deformed so as to enter the cut-away portion of the heddle bar and prevent separation of said bar therefrom, and means to normally prevent separation of the other side section from the opposite end of said heddle bar.

15 2. A tape selvage frame, comprising side and connecting end sections, said side sections being provided with a pair of aligned apertures, a heddle bar extending through said apertures and itself having a cut-away portion positioned in alignment with one side section, said last-mentioned side section being deformed so as to enter the cut-away portion of the heddle bar and prevent separation of said bar therefrom, said bar having a second cut-away portion and means extending into said second cut-away portion and cooperating with the adjacent side section to prevent separation of last-mentioned side section from said bar.

20 3. A tape selvage frame, comprising side and connecting end sections, said side sections being provided with a pair of aligned apertures, a heddle bar extending through said apertures and itself having an aperture positioned in alignment with one side section, said last-mentioned side section being deformed so as to enter the aperture in said position of the heddle bar and prevent separation of said bar therefrom, said bar having a second aperture and means extending into said last-mentioned aperture and cooperating with the adjacent side section to prevent separation of said last-mentioned side section from said bar.

25 4. A tape selvage frame, comprising a pair of U-shaped angular members, the ends of said members paralleling and overlying on each other and being unitarily secured together to form relatively rigid end sections connected by laterally yielding, resilient side sections, said side sections being provided with a pair of aligned apertures, a heddle bar extending through said apertures and itself having a cut-away portion positioned in alignment with one side section, said side section being deformed so as to enter said cut-away portion and prevent separation of said bar therefrom.

30 5. A tape selvage frame, comprising a pair of U-shaped angular members, the ends of said members paralleling and overlying on each other and being unitarily secured together to form relatively rigid end sections connected by laterally yielding, resilient side sections, said side sections being provided with a pair of aligned apertures, a heddle bar extending through said apertures and itself having a cut-away portion positioned in alignment with one side section, said side section being deformed so as to enter said cut-away portion and prevent separation of said bar therefrom, and means to normally prevent separation of the other side section from the opposite end of said heddle bar.

35 6. A tape selvage frame, comprising a pair of U-shaped angular members, the ends of said members paralleling and overlying on each other and being unitarily secured together to form relatively rigid end sections connected by laterally yielding, resilient side sections, said side sec-

tions being provided with a pair of aligned apertures, a heddle bar extending through said apertures and itself having a cut-away portion positioned in alignment with one side section, said side section being deformed so as to enter said cut-away portion and prevent separation of said bar therefrom, said bar having a second cut-away portion, and means extending into said second cut-away portion, and cooperating with the adjacent side section to prevent separation of said last-mentioned side section from said bar.

7. A tape selvage frame, comprising side and connecting end sections, said side sections being provided with a pair of aligned apertures of ir-

regular shape, and a resilient U-shaped bail comprising hooked end portions normally entering and having a shape complementary to said apertures to prevent relative oscillation between said frame and said bail.

8. A tape selvage frame, comprising side and connecting end sections, said side sections being provided with a pair of aligned longitudinally elongated apertures, and a resilient U-shaped bail comprising flattened hooked end portions normally entering and substantially filling said apertures, to maintain said bail in alignment with said frame.
